UNITED STATES PATENT OFFICE.

EUGÈNE MOREAU, OF NEW YORK, N. Y.

ACETYLENE-GAS GENERATOR.

No. 805,086.

Specification of Letters Patent.

Patented Nov. 21, 1905.

Application filed June 25, 1901. Serial No. 65,920.

To all whom it may concern:

Be it known that I, EUGÈNE MOREAU, a citizen of the Republic of France, residing at New York, in the county of New York and State 5 of New York, have invented a certain new and useful Valve, of which the following is a specification.

The object of the present invention is to provide a reliable valve which shall automatically open when in one position and which shall automatically close when turned into any other position or positions and which shall again automatically open when returned to the position first hereinabove referred to.

Another object of the invention is to provide a valve especially adapted for the gasway of portable acetylene-generators or table-lamps by reason of its remaining open only when the generator or table-lamp is in upright position and of its being automatically closed in the event of the overturning of the generator or table-lamp, whereby passage of water through the gasway is prevented and absolute safety insured.

To these and other ends hereinafter set forth the invention, stated in general terms, comprises a valve and its seat and a pendant afforded movement in all directions and adapted to control the positions of the parts of the 30 valve in respect to each other.

The nature, characteristic features, and scope of the invention will be more fully understood from the following description, taken in connection with the accompanying drawings, forming part hereof, and in which—

Figure 1 is a view illustrating, principally in central section, a valve embodying features of the invention and showing the parts in position for opening the way through the valve.

Fig. 2 is a similar view illustrating the position of the parts of the valve whereby the valveway is automatically closed, and Fig. 3 is a similar view illustrating the valve of my invention in application to an acetylene portable table-lamp.

In the drawings, 1 is the valveway. 2 is the valve, and 3 is a pendant. The pendant tends to hang vertically, and when the parts 1 and 2 or the structure which carries them is shifted out of predetermined position the pendant by reason of its weight operates to shift the part 2 in respect to part 1 in such a way that the valveway is closed. As illustrated, the valve 2 is of the plunger type and is 55 provided with a suitable face 4, as of rubber,

and it works in an opening formed for its reception in a spider 5, provided with openings 6. The spider in turn is carried by a casing 7, so that the valveway may be described to be through the inlet 8, through the casing 7, 60 through the openings 6, and through the part 1. The opening in the spider is provided with a flange or rim 9, and the stem or shank of the pendant is provided with a head 10. When the casing is turned out of its proper position 65 in any direction—for example, into the position shown in Fig. 2—the pendant 3 tries to assume under the influence of gravity an upright position. In doing so one portion of the head 10 turns about the rim 9 as a ful- 70 crum, and the diametrically opposite portion of the head 10 pushes upon the valve 2, and thus shifts it and holds it against the seat 1. Since the head 10 and rim 9 are circular, it follows that the described operation will occur no matter in which way the casing may 75 be tipped from its normal position.

In Fig. 3, 11 is a water-chamber, and 12 is a carbid-chamber. 13 indicates mechanism forming no part of this invention and which 80 is so constructed that it normally prevents the passage of carbid to the water and water to the carbid, so that it would, in case the lamp were overturned, not permit of the passage of water. 14 is the pipe by which gas is normally led from the water or generating chamber to the carbid-chamber, and by providing this pipe with the described valve it is clear that should the lamp be overturned or, in fact, turned out of its upright position the valve 85 operating in the manner described will close this passage automatically, and thus prevent water from reaching the carbid and in that way obviate all possibility of danger.

It will be obvious to those skilled in the art 90 to which the invention relates that modifications may be made in details without departing from the spirit thereof. Hence I do not limit myself to the precise construction and arrangement of parts hereinabove set forth 95 and illustrated in the accompanying drawings; but,

Having thus described the nature and objects of the invention, what I claim as new, and desire to secure by Letters Patent, is— 100

The combination of a casing having a valveway, a spider carried by the casing and provided with a cylindrical passage, a plunger-valve seated in said passage, and a normally vertical pendant having a shank provided with 110

a circular head, said spider having ports or ways and an opening through which the shank of the vertical pendant works, said opening having a flange or rim, the arrangement being such that when the casing is turned out of its proper position a portion of the circular head turns about the rim as a fulcrum while the diametrically opposite portion of the head pushes upon the valve and shifts and

holds it against its seat, substantially as described.

In testimony whereof I have hereunto signed my name.

EUGÈNE MOREAU.

In presence of—
F. G. B. GREEN,
M. TURNER.
